MULTIPLE COOKER

De Ella B. Mayberry, Detroit, Mich.

Application August 6, 1935, Serial No. 35,006

1. Claim. (Cl. 126—33)

This invention relates to a multiple cooker for use as equipment in connection with lunch stands, lunch rooms, dining rooms, restaurants, dining cars, as well as in any other connection for which it may be found applicable.

The principal object of the invention is to provide an efficient multiple unit cooker having one of the units constituting a heating source and with said units so constructed and arranged as to be comparatively inexpensive to operate and adapted to be readily regulated to vary the heating capacity of the units in accordance with different cooking requirements.

The invention further aims to provide, in a manner as hereinafter set forth, a multiple unit cooker which is comparatively simple in its construction and arrangement, strong, durable, compact, pleasing in appearance, comparatively inexpensive to manufacture, and readily assembled.

To the above ends, and to others which may hereinafter appear, the invention consists of such parts, and such combination of parts as fall within the scope of the invention as claimed.

25 In the drawings:—

Figure 1 is a detail sectional view of one of the cooker units illustrating a fire box forming part of such unit.

Figure 2 is a section on line 2—2, Figure 1. Figure 3 is a section illustrating the manner in which the cooking unit constituting the hot plate is heated.

The multiple cooker includes a cooker unit 4 in the form of a stove and a hot plate unit 3 extending from one side thereof.

The unit 4 comprises a metallic base frame 7 inset as at 8 to provide a shoulder 10 around the base and formed with an inwardly extending flange 9. A plate 12 forming the bottom of an ash pit is supported by arms 11 on said flange. An open bottom metallic housing 16 is suitably secured to the base 7 and on the shoulder 10. The housing 16 comprises a top wall 17, a rear wall 18, side walls 19 and 20, respectively, and a front wall 21. Opposed to walls 18, 19, 20, and 21 and spaced therefrom are vertical partition members 22, 23, 24, and 25, respectively, of heat insulating material, the members 22, 23, and 24 extending to a point adjacent the top 17 and the member 25 being of less height. A horizontal partition member 34 connects the members 22, 23 and 24 at their top. The partition members 22, 23, 24, 25, and 34, together with the walls 17, 18, 19, and 20, form air chambers 26 to which air is admitted through openings

14 in the base 7. Upper and lower door openings 31 and 32 are formed in the wall registering with similar related openings 27 and 28 in the partitions 25. Door frames 29 and 30 extend between related openings 27 and 31 and 28 and 32 and are closed by upper and lower doors 33 and 33' respectively.

Spaced from the partitions 21, 22, 23, 24 is an open top fire box 41 formed by short metallic side and rear partitions 36 and 37 secured to angle irons 15 on flange 13, said partition being lined with fire brick 40 resting upon a grate 39. The plate-like frame 38 closes the space between said partition 36 and 37 and 21, 22, 23, and 24 at the top of the fire box 41. A pair of water back structures comprising, on the one hand, elements 42, 44, 45, and on the other, elements 43, 46, 47, are shown in the drawings, also a water coil structure including parts 41, 48, 49, 50, 51, 57, 58, 60, and 61, but these structures need merely be identified in passing since they form, per se, no part of the present invention.

Above the fire box 41 is an oven 63 in the form of an open front casing element 64 suitably connected to housing wall 21, to seat upon partition member 25. The front of the oven may be closed by a suitable door not shown. The oven 63 is spaced from the members 22, 23, 24, and 34 to provide for circulation of heat around said oven and is also spaced from the fire box structure to provide a heating chamber 62 between said oven and structure communicating with the space between the oven and said members. A flue 63' extending from the space surrounding said oven

63 provides an outlet for chamber 62. Interposed in the chamber 62, between the frame 38 and oven 63, and over the fire box 41, is a curved deflector 65 for directing heat from said chamber 62 into the unit 3. The deflector 65 is shorter than the chamber 22 to provide for the passage of heat around the same to said oven. The deflector 65 is provided intermediate its ends with an opening 66 adapted to be closed by a damper 67 suitably mounted for operation exteriorly of the unit 4 as by lever 65' shown in dotted lines in Figure 3. The deflector 65 coacts with a flue 68, a deflecting plate 69 and an opening 70 in housing wall 19 to direct heat from the fire box 41 and chamber 62 into unit 3. The flue 68 is mounted in member 23 in the opening 70 and the deflector 65 extends from a point contiguous the top of said flue to direct heat into the latter.

The unit 3 comprises an open top and open rear casing 73 of heat insulating material form- 55

ing a heating chamber 73' into which the flue 68 opens. A baffle plate 74 is provided in said casing for directing the heat and products of combustion received from unit 4 to an outlet 75 5 in said casing opening into an upstanding stack 76 which communicates with the flue 63'. A metallic housing 77 encloses the casing 73 in spaced relation thereto and is mounted on suitable supports 80. A metallic hot plate proper 10 78 covering the casings 73 and housing 77, is disposed thereover, said plate having an overhanging curved flange 79 for a purpose which will be apparent. Preferably the casing 73, housing 77 and hot plate 78 are anchored to the 15 housing wall 21.

When it is desired to utilize the maximum heating capacity of the unit 3, the damper 67 is closed whereby the major part of the heat from the fire box 41 will be directed into said 20 hot plate unit as will be clear. By manipulating the damper 67 to different positions the amount of heat passing to said unit 3 may be decreased and heat by-passed from beneath the deflector 65 to said oven whereby the amount of heat

passing to said unit 3 and the oven 63 may be varied in accordance with different cooking requirements.

What I claim is:

A cooking unit comprising an open top fire box, an oven above said fire box and spaced therefrom to provide a heating chamber between said box and oven, a second cooking unit extending from one side of the first mentioned unit, said second unit including a hot plate and having a 10 heating chamber under said plate provided with an inlet flue opening into the first mentioned heating chamber, a deflector plate extending from a point contiguous the top of said flue into the first mentioned heating chamber for directing heat from the latter into said flue, said deflector plate being shorter than said first mentioned chamber to provide for the passage of heat around the same to said oven, and a damper in said deflector plate for by-passing heat from beneath the latter to said oven and thereby varying the degree of heat passing to said hot plate and oven respectively. 15 20
